G. M. MINTON,
HOLDER FOR MEMORANDA STRIPS OR GAME SCORES,
APPLICATION FILED DEC. 20, 1917. RENEWED MAY 28, 1921.
1,388,365.

Patented Aug. 23, 1921.

UNITED STATES PATENT OFFICE.

GUSTAVE M. MINTON, OF NEW YORK, N. Y., ASSIGNOR TO LEO SCHLESINGER & CO., OF NEW YORK, N. Y., A FIRM COMPOSED OF LEO SCHLESINGER, GUSTAVE M. MINTON, AND BENJAMIN LEVY.

HOLDER FOR MEMORANDA-STRIPS OR GAME-SCORES.

1,388,365.

Specification of Letters Patent. Patented Aug. 23, 1921.

Application filed December 20, 1917, Serial No. 208,029. Renewed May 28, 1921. Serial No. 473,319.

To all whom it may concern:

Be it known that I, GUSTAVE M. MINTON, a citizen of the United States, and a resident of the city, county, and State of New York, have invented certain new and useful Improvements in Holders for Memoranda-Strips or Game-Scores, of which the following is a specification.

The present invention relates to a device for holding a memoranda strip or game score sheet in convenient position for writing and for holding a sheet supply in the form of a roll from which new sections may be drawn from time to time. It also includes simple means for holding down the section of the sheet which has been drawn out to be written on, of a base or platen for this portion of the sheet, of a suitable holder for the paper roll, a clip for holding the device on the edge of a table or other support, and a ruler or edge against which the paper may be torn to remove the used portions.

The device is very simple, inexpensive and convenient. I have provided a device which is especially useful for keeping game scores, for instance, for keeping scores in bridge whist, but it will be obvious that the device may be used for many other purposes.

In the drawing forming part of this application—

Figure 1 is a perspective view of my invention applied to a table ready for use.

Fig. 2 is a longitudinal sectional view taken on the line 2—2 of Fig. 1.

Fig. 3 is a sectional view taken on the line 3—3 of Fig. 2, and

Fig. 4 is a sectional view taken on the line 4—4 of Fig. 1.

The member on which the active portion of the paper strip is adapted to rest consists of a base or platen 1 preferably flat, and it is intended to rest on a table top 2 or other convenient support. It is of sufficient area to provide for writing over an appreciable area of the paper strip 3. At one end of the platen 1 the metal is curved into a cylindrical casing 4 which receives endwise therein a roll 5 of paper. The casing 4 is so formed that it lies below the plane of the platen 1 so as not to interfere with the hand which rests on the platen while writing, and its free edge 6 is spaced slightly from the end of the platen to provide a cross slot 7 through which the paper strip may be drawn out and laid flat over the top of the platen. The tubular casing 4 is preferably, though not necessarily, made of metal and it is more or less resilient, so that the caps 8 may be sprung over the ends of the circular casing or holder and be held in place by the tendency of the latter to open or spread. The caps 8 are knurled at 9 to provide a proper gripping surface and they are provided with means for centering or holding the roll in proper position in the casing to keep the edges of the paper strip away from the caps. I have shown each cap provided with a cup shaped member 10 on the inner side of the cap. These cup members are small enough to be received in the casing 4 and they extend beyond the edges 11 of the caps 8 in order to hold the paper roll centered where the edges of the latter will not rub against the edges 11 and be torn when the strip is drawn off from the roll.

Clips 12 are provided on the under side of the platen 1. They preferably are curved over and soldered to the casing 4 at 13 and they then extend forwardly to a position under the platen, and they are sufficiently bowed to provide the desired resiliency. The forward ends of the clips are adapted to co-operate with the platen 1 to grip on the edge of a table top 2 or other support in order to hold the device in convenient position and to permit the user to write without having to hold the device.

On the front of the casing and below the plane of the platen, I provide a convenient holder to retain the pencil when not in use and in the drawing this is shown as a tube 14 attached to the casing 4 and into which a pencil may be inserted endwise.

I provide a member for holding the active portion of the paper strip flat and this member preferably "frames" the strip, *i. e.*, forms a frame around the edges. The frame 15 consists of cross members 16 hinged at 17 to the casing 4, of longitudinal side portions 18 extending from the portions 17 and of an end portion 19. These several parts comprise a rectangular (or any other shape) frame which when lowered, rests on the strip 3 and against the platen 1 around the side edges and across the free end of the paper strip. The cross member 19 of the frame is provided with an edge member 20 against which the paper strip may be torn.

In the drawing I have shown a paper strip

ruled and marked at 21 to represent a blank for keeping score in bridge whist and these markings are repeated at regular intervals throughout the whole strip, but it will be understood that the strip may consist of plain paper or it may be provided with markings other than those designated.

- In using the device, the platen 1 is pushed over the edge of the table 2 so that the clips 10 12 engage the under surface and clamp the device in the position shown in the drawing. One of the caps 8 is then removed and a roll 5 of paper is placed endwise into the casing and the outer end of the strip is carried 15 through the slot 7. The cap 8 may then be replaced. The strip 3 is then drawn through the slot 7 and its end is carried to the forward end of the platen, the frame being swung back during this operation, free of the platen 20 and of the strip. When the strip has been drawn out to overlie the platen the frame 15 is swung down to rest thereon. The device is now ready for use. It will be obvious that the user may write on the extended portion 25 of the strip and against the platen lying under it and as the device is itself held on the table by the clips, and the extended portion of the strip is held down by the frame 15 it is unnecessary to hold the device or the 30 strip in order to write on the latter. The writing hand may rest freely over the platen

and there is nothing to obstruct its movement. When the extended portion 3 of the strip has been used it is only necessary to grasp the forward end, pull out the strip 35 until a new section lies over the platen 1 and the used section can then be removed by tearing it upwardly against the edge 20. This may all be done without raising the frame 15. It is very easy to attach the device to any 40 table, desk or other support having a free edge to receive the platen and clips over and under it.

Having described my invention, what I claim is:

A device of the class described including a platen, means for holding the platen thereon with one end projecting beyond the support, a tubular casing for holding a supply of paper for use on said platen, arranged beyond 50 the support and below the plane of the platen, said casing having a slot in the top from which the paper is adapted to be drawn over the platen and a frame hinged to the tubular casing beyond said slot and extending over said slot and platen and adapted to hold the extended portion of the paper on the latter.

Signed at the city, county and State of New York this 25th day of October, 1917.

G. M. MINTON.
